DAM

Alfonso Peña Boeuf, Madrid, Spain

Application March 22, 1933, Serial No. 662,043
In Spain March 23, 1932

9 Claims. (Cl. 61—30)

This invention has for its object to provide new features of construction relating to arched dams, applicable to large and small valleys, as the most suitable and economical means of damming 5 water for industrial purposes.

Heretofore arched dams have been constructed having a continuous foundation of concrete and comprising a solid mass at the sides as well as at the bottom.

10 The problem of making, with regard to such dams, calculations taking into account certain important variations of conditions, is insoluble owing to the great complications that occur in making such calculations respecting any solid 15 body which is subjected to reactions due to forces applied at various parts of its outer surface, and for this reason arched dams of the present day have been calculated on the basis of the assumption that at each point of the middle area of 20 the dam there intersect two strips which are of unit width and of which one is in the form of an arch in horizontal section and the other is straight in vertical section. These two strips, the 25 first being considered as an arch fixed at the sides of the valley, and the second as a straight portion fixed at the bottom, have equal deflections where they meet because they are calculated so as to give equality of deformation at this point.

This method of calculation, commonly employed for present day arched dams by Swiss 30 and German engineers, and which, because it is considered to be the most satisfactory, is the one usually adopted for planning such works, suffers from the defect that the two strips previously 35 mentioned as serving as a basis of calculation are treated as being independent of their surroundings, so that their reactions are not taken into consideration and the calculations do not take into account the variations of the working loads 40 and of their distribution.

Now it is an object of this invention to provide new features of construction to be used in building arched dams that will avoid these errors of calculation and that possess other advantages 45 which will be hereinafter mentioned and from which a saving of more than 50 percent. is anticipated.

In the drawings illustrating forms of dam construction embodying the invention in its preferred form:

Figure 1 is a plan view of a portion of a narrow valley closed by a single unit of dam construction having features of the invention embodied.

55 Figure 2 is a transverse section through the

valley illustrated by Figure 1, the dam being shown in elevation.

Figure 3 is a large scale, vertical, cross-sectional view of a portion of the dam construction, the section being cut through one of the horizontal joints near the upstream side of the structure.

Figure 4 is a plan view of a portion of a dam embodying the invention in a form adapted to obstruct a relatively wide valley.

Figure 5 is a small scale, vertical, cross-sectional view of a valley closed by a dam construction 10 of the form of the one shown by Figure 4.

Figure 6 is a large scale, horizontal, cross-sectional view of a portion of the dam construction shown in Figures 4 and 5, the section being cut 15 through the adjacent springers of a pair of arch sections and the abutting portions of an intervening buttress.

Figure 7 is a large scale elevational view of the 20 upper portion of one of the buttresses and a portion of the crest of the dam illustrated in Figures 4 and 5.

Figure 8 is a large scale, horizontal, cross-sectional view of a portion of an arch section of a 25 dam construction embodying the invention, the section being cut through a springer, its abutment, a portion of the valley wall in which the abutment is embedded and the vertical joint between the springer and its abutment.

As shown by Figures 1, 2 and 3, a dam embodying the invention in a form adapted to obstruct a valley that is not very wide may comprise a plurality of arch-like sections, *c*, which extend from one side of the valley to the other with their springers, *d*, in abutting relations with opposing portions of the valley walls, or with abutments, *d'* (Figure 8), embedded therein, the sections being superimposed one upon another with layers, *b*, Figure 3, of suitable plastic material, such as asphalt, in their intervening horizontal joints, *e*, and in the joints, *a*, between the springers and their abutments (Figure 8), to enable contacting portions of the sections to move one with respect to the other and to provide slightly yielding seats between the springers and 40 the abutments.

A very great advantage of this mode of construction is that each arc-shaped strip or section can be readily calculated as an independent arch subjected to compressive forces only and 50 the radius of each arch section, see Figure 1, can be chosen so as to bridge the distance between the sides of the valley in the most suitable manner.

Another great advantage of this mode of con- 55

buttresses and the arc-shaped strips of the dam,—are of uniform unreinforced concrete.

The arc-shaped strips may be molded between metal frames having the forms of the intrados 5 and the extrados. It is sufficient to place four of these frames outside and four inside, to secure them in place to prevent them from moving apart, and to provide vertical boards supported outside and inside on these frames. In this way 10 there is formed a mould for an arc-shaped strip of three meters in height which is supported on a low arc-shaped strip already made, so that there is no necessity for scaffolding or special moulds.

15 I claim:

1. A dam comprising, in combination, a plurality of units disposed in end-to-end relation, each unit comprising a plurality of arch-like sections having intervening, horizontal, yielding joints along which the parts of each may be caused to move with respect to adjacent parts of the overlying and underlying structure, the opposed surfaces at each horizontal joint being relied upon as the means whereby the weight of 20 the overlying part of the structure may be transmitted to the underlying part without preventing such relative movement, the various sections being effective as substantially independent arches each capable of transmitting to its springers, as a substantially independent unit, the forces resulting from the pressures exerted 25 against its upstream surface and of yielding substantially independently of the adjacent overlying and underlying sections in response to such pressures, a buttress of the gravity type being provided for the adjacent ends of each pair of units, the buttresses having portions to serve as abutments for the adjacent pairs of springers of 30 their various arch-like sections.

40 2. A dam of the arched type comprising, in combination, a plurality of arch-like sections and their abutments, the sections having intervening horizontal slip-joints along which the parts of each may be caused to move with respect to adjacent parts of the overlying and underlying structure and vertical slip-joints between their 45 springers and their abutments, the opposed surfaces at each horizontal joint being relied upon as the means whereby the weight of the overlying part of the structure may be transmitted to the underlying part without preventing such relative movement, the upstream and downstream 50 surfaces of each section being substantially cy-

lindrical and substantially concentric and the joints between its springers being substantially radial, the various sections being substantially independent arches, each capable of transmitting to its springers, as a substantially independent unit, the forces resulting from the pressures against its upstream surface and of yielding substantially independently of the adjacent overlying and underlying sections in response to such pressures.

3. A dam, as defined by claim 2, having layers 10 of yieldable material in the horizontal joints between its arch-like sections.

4. A dam, as defined by claim 2, having layers 15 of yieldable material in the vertical joints between the springers of its arch-like sections and their abutments.

5. A dam, as defined by claim 2, having layers 20 of yieldable material in the joints between its arch-like sections and between the springers of the sections and their abutments.

6. A dam of the arched type comprising, in combination, a plurality of substantially independent, integral, horizontal, arch-like sections and their abutments, the respective sections being 25 of relatively small height as compared with the height of the dam and being isostatically supported by having yielding, intervening, horizontal joints and by having yielding, vertical joints between their springers and their abutments, 30 with the vertical joints disposed in planes passing through the radii of curvature of the sections adjacent the respective joints, whereby the respective sections may be of spans and horizontal depths most appropriate to close the gaps to be 35 dammed and to withstand the pressures to be resisted at different levels, and the parts of the respective sections subjected to compressive stresses only, in resisting pressures directed 40 against their upstream faces, all of the joints being provided with adequate sealing means to render the structure substantially impermeable.

7. A dam, as defined by claim 6, having layers 45 of yielding material interposed between the opposed surfaces at its horizontal joints.

8. A dam, as defined by claim 6, having layers 50 of yielding material interposed between the opposed surfaces at its vertical joints.

9. A dam, as defined by claim 6, having layers 55 of yielding material interposed between the opposed surfaces at its vertical and horizontal joints.
